U.S. Appl. No. 29/875,370, filed May 3, 2023, by Braff et al.

(Continued)

Primary Examiner — Keli L Hill(74) *Attorney, Agent, or Firm* — Michael Best &
Friedrich LLP(57) **CLAIM**

The ornamental design for a loudspeaker, as shown and described.

DESCRIPTION

FIG. 1 is a front, top, right perspective view of a loudspeaker according to the present invention;

FIG. 2 is a rear, top, right perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof; and,

FIG. 8 is a bottom view thereof.

The broken lines illustrate portions of the loudspeaker that form no part of the claimed design.
